UNITED STATES PATENT OFFICE.

WARREN W. CARPENTER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 21, 1923. Serial No. 663,962.

To all whom it may concern:

Be it known that I, WARREN W. CARPENTER, a citizen of the United States of America, residing at Queens, in the county of 5 Queens and State of New York, have invented certain new and useful Improvements in Telephone-Exchange Systems, of which the following is a full, clear, concise, and exact description.

10 This invention relates to multi-exchange telephone systems and more particularly to two-way inter-exchange trunk circuits therefor.

15 The object of the invention is to improve the operating efficiency of circuits of this character.

20 A feature of the invention is a circuit arrangement whereby an established connection between operators at opposite ends of a trunk line is momentarily broken down and reestablished in the opposite direction in case the operator originating the connection "flashes," that is, alternately disconnects from and connects to the trunk for the purpose of attracting the distant operator's attention, whereby improved supervision and operation of devices for holding the trunk line busy during the flashing interval is secured over circuits of the character described having relatively low resistance 25 leaks to ground.

30 More specifically, when the operator originating the connection removes and reinserts her connecting plug, a battery, which was included in a relatively low resistance bridge across the trunk at the originating or calling end when the connection was first established, is removed and a similar battery connected in a relatively low resistance 35 circuit across the distant or called end of the trunk which in effect is the same condition as would be created if the connection had been originated at that end of the trunk. The continued removal and insertion of the 40 originating operator's plug then causes the resistance of the bridge circuit at the calling end to be alternately increased and reduced sufficiently to cause the alternate release and operation of a relay in the battery circuit at the called end of the trunk, which relay controls a supervisory signal appearing before the operator. During the interval between the removal and reinsertion of the plug, a

busy guard is placed on the trunk to prevent its being seized by another operator or automatic switch. 55

Other features not specifically mentioned above will more readily appear from the following description and drawings, in which a trunk circuit embodying the invention is shown together with sufficient connecting apparatus to properly illustrate the invention. 60

Referring to the drawings;

Figs. 1 and 2 show a portion of a private 65 branch exchange adapted for both automatic and semi-automatic working in which one end of an inter-exchange trunk line terminates.

Figs. 3 and 4 show a portion of a similar 70 exchange at the distant end of the trunk.

At each exchange provisions are made for terminating dial station lines in automatic switches, not shown, which switches have access to both the operator and the trunk. 75

Figs. 1 and 4 show incoming selector switch circuits at the two exchanges arranged to be controlled by current impulses transmitted over the trunk circuit from the distant end to signal the exchange operator, 80 or to connect the trunk to a called dial station line.

A detailed description of the operation of the system of the invention will now be given. 85

Let us assume that an operator at the exchange represented by Figs. 1 and 2 has answered a call by inserting her answering plug AP into the jack (not shown) of a calling line, and desires to converse with the operator at the distant exchange, Figs. 3 and 4, and accordingly inserts the plug 200 of her cord circuit in the jack 201 associated with the trunk L_1, L_2 . 90

When plug AP was inserted in the jack of the calling line it will be assumed that ground was encountered on the sleeve of the jack thereby causing the lighting of supervisory lamp C in an obvious circuit. Supervisory lamp A does not light if it is assumed that a call was awaiting the insertion of plug AP as in such a case the answering cord supervisory relay AS operates in an obvious circuit including the closed loop of the calling line, thereby disconnecting lamp A at the back contact of the relay. Lamp 95 100 105

C continues to burn after plug 200 is inserted in jack 201 and until the called operator answers as will later appear.

When the plug 200 is inserted in the jack 201, relay 202 operates in the following circuit, battery, relay 202, contacts 203 of jack 201, contacts 204 of relay 205, and contacts 206 of relay 207 to ground. Relay 202 in operating, closes its contacts 208 thereby closing a locking circuit for itself which may be traced from battery, winding of relay 202, contacts 203 and 208 to ground. Relay 202 in operating, also closes operating circuits for relays 209 and 210. The circuit for relay 209 can be traced from battery, winding of relay 209, and contacts 211 of relay 202 to ground. The circuit for relay 210 is traced from battery, through the winding of that relay, contact 212 of relay 213 and contact 214 of relay 202 to ground. Relay 209 in operating, connects ground through its contacts 215 to the sleeve conductor 247 leading to the multiple terminals CM of a connection switch not shown, thus putting a busy condition on the test terminal of the switch to prevent the trunk from being seized in case a dial subscriber attempts to call the distant exchange. Closure of contacts 215 also supplies ground to operate relays 216, 207 and 217, the circuits for which are as follows: In relay 216, the circuit extends from battery, through the winding of that relay, and the contacts 215 of relay 209 to ground, and for relays 207 and 217 parallel circuits extend from battery, through the windings of these relays, contacts 218 of relay 219, contacts 220 of relay 221, contacts 222 of relay 223 and contacts 215 of relay 209, to ground. Relay 216 operated connects ground to the sleeves of the trunk jacks as a busy guard. Relay 207 in closing its contacts 224 completes a locking circuit for itself which may be traced from battery, winding and contacts 224 of relay 207, contacts 222 of relay 223 and contacts 215 of relay 209 to ground. Relay 217 is also held to ground through the above traced circuit. Relay 207 in operating, also closes an energizing circuit for relay 225 which may be traced from battery, winding of relay 225, contacts 226 of relay 227, and contacts 228 of relay 207 to ground. Relay 225 in operating, closes an obvious energizing circuit for relay 219 and also connects direct ground at its contacts 229 to hold relays 207 and 217 energized for a reason which will later appear. Relay 217 in operating, completes a circuit for connecting relays 230 and 231 in series with relay 330 at the distant end of the trunk which can be traced from battery, relay 231, contacts 234 of relay 217, contacts 235 of relay 210, contacts 236 of relay 223, lower right winding of repeating coil 233, conductor L₂, lower left winding of repeating coil 333, contacts 336 of relay 323, con-

tacts 338 of relay 307, contacts 339 of relay 340, contacts 337 of relay 310, contacts 341 of relay 317, winding of relay 330, upper left winding of repeating coil 333, conductor L₁ of the trunk, upper right winding of the repeating coil 233 (Fig. 2) winding of relay 230 and contacts 232 of relay 217 to ground. 70

Relay 330 at the distant end of the trunk in operating, prepares the equipment thereat for receiving the impulses to be sent, by closing the circuit for the pulse relay 400 (Fig. 4) of the incoming selector, the circuit of which can be traced from grounded battery, left-hand winding of relay 400, contacts 401 of relay 402, conductors 404 and 351, contacts 342 of relay 343, winding of relay 321, contacts 344 of relay 305, contacts 345 of relay 330 and contacts 346 of relay 317 to ground. Relay 321 operates in this circuit and connects ground to the sleeve conductor 347 thus placing a busy condition on the test terminals CM' of a connector switch (not shown) to prevent the trunk from being seized by a dial subscriber. This circuit can be traced from ground, contacts 348 of relay 321 and contacts 322 of relay 323 to conductor 347. Ground on the conductor 347 also operates relay 316, which in operating, connects ground to the sleeves of the trunk jacks as a busy guard. Relay 321 in operating, also closes a circuit for the operation of relay 325 which can be traced from battery, relay 325 and contacts 349 to ground. Relay 325 in operating, closes at its contacts 350 an obvious circuit for the energization of relay 319. The closure of contacts 329 of relay 325 also connects ground at this point to conductor 347 thus holding a busy condition on the connection switch multiple CM' for a short time after the release of relay 321 due to the fact that relay 325 is slow-to-release, which will be referred to later. 90

Relay 319 in operating, closes a circuit for the operation of relay 403 which can be traced from battery, relay 403, conductors 405 and 352, contact 353 of relay 343, contacts 354 of relay 319 and contacts 346 of relay 317 to ground. 100

Relays 400 and 403 now being energized, the selector is ready to receive pulses and the next step is the operation at the calling exchange of the dialing key 255 which closes an obvious circuit for the operation of relay 213 and lights the dial pilot lamp 256. Relay 213 in operating, transfers the ground for holding relay 210 operated, from contacts 214 of relay 202, to contacts 257 of dial 258. Relay 213 in operating, also closes at its contacts 259 and 260 short circuits around the upper and lower right hand windings respectively of repeating coil 233. 115

It will be assumed that zero is the digit to be dialed to signal the distant operator.

When the dial 258 is operated, the impulse contacts 257 interrupt a circuit through 120

130

relay 210 and as the dial returns to normal, relay 210 releases and operates in unison therewith. The first time relay 210 releases, the trunk line loop circuit through relay 230, 5 231 and 330 previously traced, is opened at contact 235 thus releasing relays 230 and 330. Relay 230 in releasing, performs no useful function at this time. As relay 210 releases and closes its contacts 237, a circuit is closed 10 for the operation of relay 227 which can be traced as follows: battery, winding of relay 231, contacts 234 of relay 217, contacts 237 of relay 210, winding of relay 227 and contacts 261 of relay 217 to ground. Relay 227 15 operates in this circuit and relay 231 is held operated. Relay 231 is sluggish and therefore does not release during the period between the opening of contacts 235 and the closing of contacts 237. Relay 227 in operating, opens at its contacts 226 the energizing circuit of relay 225 but since this relay is sluggish, it holds up over the dial pulses. Relay 227 in operating, also connects battery through resistance 262, to the conductor L_2 of 20 the trunk, thus reoperating relays 230 and 330. This circuit may be traced from battery, resistance 262, contacts 263 of relay 227, contacts 236 of relay 223, contact 260 of relay 213 to conductor L_2 . It will 25 be noted that the trunk loop is opened and relays 230 and 330 released only during the interval between the release of relay 210 and the operation of relay 227. When contacts 257 of the dial again close relay 210 is 30 reoperated and the circuit through the winding of relays 227 and 231 is opened at contacts 237. When contacts 235 of relay 210 close, relays 230 and 330 are connected in series with relay 231 to battery again instead 35 of through resistance 262 which is disconnected upon the release of relay 227. Relay 227, however, does not release until after contact 235 of relay 210 closed due to the 40 charging of condenser 264 bridged across the contact 237 thereby preventing a false impulse being sent out due to the release of relay 227 before contacts 235 of relay 210 close. The above cycle of operation occurs 45 for each impulse sent from the dial thus re-laying the impulses over the trunk to the distant incoming selector or connector which advances the automatic mechanism thereto to the desired level which, in the system described, is assumed to be the tenth or zero 50 level.

The operation of the selector switch (Fig. 4) in response to the alternate operation and release of relay 400, will not be discussed in detail as the operation of such apparatus is 55 well known to those familiar with automatic telephone circuits, it being sufficient to mention that the vertical magnet 406 is operated when relay 400 releases on the first interruption of the dial contacts 257 in a circuit which can be traced as follows: battery, 60 vertical magnet 406, relay 408, contacts 407 of relay 400, contacts 409 of relay 402, and contacts 410 of relay 403 to ground. This operation of magnet 406 is repeated with each dial interruption thus stepping the 70 switch upward to the desired level which as before stated, is assumed to be the tenth or zero level, this being the position of the switch in which the contacts 411 are adapted to be closed. 75

When dialing is completed the dialing key is restored to normal thus releasing the relay 213 and extinguishing the dial pilot lamp 256. When relay 213 releases, the shunt circuits around the right-hand windings of repeating coil 233, previously traced are removed, and the holding circuit for relay 210 is transferred back to and under control of relay 202. This holding circuit now extends from battery, through the winding of relay 210, contact 212 of relay 213, and contact 214 of relay 202 to ground. 80

The closure of contacts 411 by the switch of Fig. 4 moving into the 10th level connects ground to conductors 412 and 365 to operate 90 relay 343 which, in operating, locks to ground in the following circuits: battery, winding of relay 343 and its contacts 370, contacts 354 of relay 319 and contacts 346 of relay 317 to ground. Relay 343, in operating, also opens at its contacts 342 the circuit for relays 321 and 400, which relays now release. At its contacts 353 relay 343 opens the circuit for relay 403 which also releases and at its left armature and back contact completes an obvious circuit of the 95 operation of release magnet 413 which then functions to restore the switch to normal. When relay 343 operates it further closes a 100 circuit for line lamp 367 which can be traced from battery, contacts 368 and 369 of relay 309, contacts 366 of relay 343 and lamp 367 to ground, thus giving the operator an indication of the call. When relay 321 released 105 it connected ground to operate relays 371, 305 and 340, the circuits for which can be traced from ground, through contacts 372 of relay 321, contacts 373 of relay 319, contacts 374 of relay 331 and thence in parallel circuits to battery, one circuit extending through contacts 375 of relay 317 and winding of relay 305 and the other through the windings of relays 371 and 340. These relays now operate and lock to ground through 110 contacts 376 of relay 371, 373 of relay 319 and 372 of relay 321. When relay 305 operates it provides a holding circuit for relay 325 which would otherwise be released due to the release of relay 321. This holding circuit can be traced from battery, winding of relay 325, contacts 377 of relay 305, contacts 345 of relay 330 and contacts 346 of relay 317 to ground. It will be noted that 115 due to the fact that relay 325 is slow to release the above traced holding circuit is 120

125

130

closed before relay 325 and relay 319 controlled by it have time to release. When relay 340 operated it closed its contacts 378 thus connecting the upper or tip terminal of the right-hand winding of repeating coil 333 to the open contacts 379 of relay 302, the lower or ring terminal being permanently connected to contact 380. Relay 340 in operating also opens its contacts 339, thus breaking the shunt connection normally around high resistance relay 381 and relay 327 and thereby inserting these relays in series with relay 330 which increases the trunk loop resistance to such a value that relays 230 and 231 release. Relay 231, in releasing, closes a circuit for the operation of relays 240 and 271 which can be traced from battery, winding of relay 240, winding of relay 271, contacts 274 of relay 231, contacts 273 of relay 219 and contacts 272 of relay 221 to ground. Relays 240 and 271 operate and lock to ground through contacts 276 of relay 271, contacts 273 of relay 219, and contacts 272 of relay 221. Relay 240, in operating, closes its contacts 278 to connect the upper or tip terminal of the left-hand winding of repeating coil 233 to the tip contacts of the jack 201 and plug 200, over the contacts 279 of operated relay 202. The lower or ring terminal of repeating coil 233 is permanently connected to contact 280, which in this case is closed thus connecting the tip and ring of the cord to the repeating coil.

The operator at the distant end of the trunk upon observing the illumination of lamp 367 inserts plug AP' in jack 301 and relay 302 operates in the following circuit: battery, winding of relay 302, contacts 303 of jack 301 and contacts 382 of relay 343 to ground. Relay 302, in operating, locks to ground at its contacts 308 in an obvious circuit and closes a circuit for the operation of relay 310 which can be traced from battery, winding of relay 310, contacts 312 of relay 313 and contacts 314 of relay 302 to ground; relay 302 in operating also closes a circuit for relay 309 which can be traced from battery through the relay 309 and to ground at contacts 311 of relay 302. Relay 310, in operating, again shunts relays 381 and 327, thus reducing the trunk line loop resistance to a point where relay 231 at the originating end of the trunk will again operate. The above shunt circuit can be traced from line conductor L_2 , lower left winding of the repeating coil 333, contacts 336 of relay 323, contacts 335 of relay 310, contacts 341 of relay 317, relay 330, upper left winding of repeating coil 333 to line conductor L_1 .

Relay 309 in operating closes a circuit to operate the supervisory relay 384 in series with the operator's answering cord supervisory relay AS' which circuit can be traced from ground supplied through the upper winding of retardation coil RC', over the

tip of the plug AP', tip contact of jack 301, contacts 379 of relay 302, contacts 378 of relay 340, upper right winding of repeating coil 333, upper winding of retardation coil 383, winding of relay 384, contacts 388 of relay 343, contacts 387 of relay 309, lower winding of retardation coil 383, lower right winding of repeating coil 333, contacts 380 of relay 302, ring contacts of the jack 301 and plug AP' and over the ring conductor of the cord through the cord supervisory relay AS' and lower winding of retardation coil RC' to grounded battery. The cord supervisory relay AS' operates in this circuit and at its back contact opens the circuit for the cord supervisory lamp A' which would otherwise be lighted in a circuit from battery through lamp A' the back contact of relay AS' and ground on the sleeve of jack 301 placed there when relay 316 operated. The talking battery connection for the called operator is now completed and the operator is connected to the switchboard side of the trunk repeating coil. It will be obvious that calling supervisory lamp C' will remain lighted until the station called over plug 300 answers.

Relay 231 at the outgoing end of the trunk in reoperating closes a circuit to operate the supervisory relay 284 in series with the operator's calling cord supervisory relay CS, which circuit can be traced from ground through the upper winding of retardation coil RC, tip of the plug 200, tip contact of jack 201, contacts 279 of relay 282, contacts 278 of relay 240, upper left winding of repeating coil 233, upper winding of retardation coil 283, winding of relay 284, contacts 285 of relay 231, contacts 287 of relay 209, lower winding of retardation coil 283, lower left winding of repeating coil 233, contacts 280 of relay 202, ring contacts of jack 201 and plug 200 and over the ring conductor of the cord through the cord supervisory relay CS and lower winding of retardation coil RC to grounded battery. The cord supervisory relay CS operates in this circuit and at its back contacts opens the circuit of supervisory lamp C which goes out. The talking battery circuit for the calling operator is now completed and she is connected to the switchboard side of the trunk repeating coil. The connection is now complete between the calling and called operators.

Flashing.

In case the calling operator Figs. 1 and 2 should find it necessary to flash, i. e., signal the called operator before the connection is broken down, she alternately removes and reinserts her plug 200 in jack 201, which causes the following operation of the relays in the circuit:

When the plug is removed from the jack, relays 202 and 284 release, which in turn,

cause the release of relays 209 and 210. When relay 210 releases, the battery bridge across the trunk including relays 230 and 231 is momentarily interrupted at contacts 235 and a circuit is closed at contacts 237 to operate relay 227 and hold 231 operated, which can be traced from battery, winding of relay 231, contacts 234 of relay 217, contacts 237 of relay 210, winding of relay 227 and to ground at contacts 261 of relay 217. Relay 227, in operating, places a substitute battery bridge across the trunk which can be traced from battery, resistance 262, contacts 263 of relay 227, contacts 236 of relay 223, lower right winding of repeating coil 233, over trunk conductor L_1 , through the low resistance bridge including relay 330 at the distant end, back over trunk conductor L_1 , upper right-hand winding of repeating coil 233, winding of relay 230 to ground at contacts 232 of relay 217. Relay 227, in operating, also releases relay 225, which in turn, releases all the other operated relays. When relays 217 and 227 released, battery and ground was disconnected from the trunk and a dry or battery free bridge including relay 230 was substituted therefor. This circuit can be traced from the upper right winding of repeating coil 233, winding of relay 230, contacts 241 of relay 217, contacts 237 of relay 210, contacts 239 of relay 240, contacts 238 of relay 207, contacts 236 of relay 223 to the lower winding of repeating coil 233. In case the plug is reinserted during the release of the above relays, the circuit does not function and the relay 202 cannot operate as its operating ground is open at the contacts of relays 205 and 207.

When relays 217 and 227 released, thus removing battery and ground from the trunk, relay 330 at the distant end of the trunk released, which in turn, opened the locking circuit for relay 325, which in turn caused relays 319, 371, 340, 305, 343 and 384 to release. When relay 319 released it closed at its contacts 318 a circuit to operate relays 317 and 307 which may be traced from ground, contacts 315 of relay 309, contacts 322 of relay 323, contacts 320 of relay 321, contacts 318 of relay 319 and thence over parallel paths through the windings of relays 307 and 317 to battery. When relay 317 operated, battery was connected to one side of the trunk L_2 through relay 331 and ground was connected to conductor L_1 through relay 330, thus completing the following circuit: battery, winding of relay 331, contacts 334 of relay 317, contacts 335 of relay 310, contacts 336 of relay 323, lower left winding of repeating coil 333, conductor L_2 , lower right winding of repeating coil 333, contacts 236 of relay 223, contacts 238 of relay 207, contacts 239 of relay 240, con-

tacts 237 of relay 210, contacts 241 of relay 217, winding of relay 230, upper right winding of repeating coil 233 to conductor L_1 , thence over the trunk to the upper left winding of repeating coil 333, through the winding of relay 330 and contacts 332 of relay 317 to ground. Relays 330 and 331 at the called or distant end of the trunk and relay 230 at the calling end of the trunk operate.

It will be noted that battery is now connected to the trunk at the distant or called end instead of at the calling end of the trunk, that is to say, instead of having a dry or battery free bridge at the called or distant end of the trunk and a wet or battery bridge across the trunk at the originating or calling end, this situation is now reversed and the bridge across the called end includes battery in series with relays 330 and 331, while the battery in series with relay 230 at the calling end has been removed, together with relay 231.

With the release of relay 340 the operator's answering cord supervisory relay AS' releases, thus lighting the cord supervisory lamp A'. The talking battery circuit at that end of the trunk is also broken at the contacts of relay 340 when it operates.

The operation of relay 230 at the calling exchange in series with distant relays 330 and 331 just mentioned, causes relay 221 to operate in series with relay 100 of the selector circuit, which circuit can be traced from battery, winding of relay 100, contacts 101 of relay 102, conductors 104 and 251, contacts 242 of relay 243, winding of relay 221, contacts 244 of relay 205, contacts 245 of relay 230 and to ground at contacts 246 of relay 217. Relays 221 and 100 operate, but the operation of relay 100 accomplishes no useful purpose at this time. Relay 221, in operating, causes the operation of relay 216 by closing a circuit which can be traced from battery, winding of relay 216, contacts 222 of relay 223 and contacts 248 of relay 221 to ground. Relay 216, in operating, closes an obvious circuit to connect ground to the sleeves of the trunk jacks. It will be evident also that the ground supplied to operate relay 216 is also extended over conductor 247 to the multiple terminals CM of a connector switch, not shown, to prevent the trunk from being seized by a dial station call.

Relay 221, in operating, also connects ground at its contacts 249 to operate relay 225 in an obvious circuit. Relay 225, in operating, closes an obvious circuit to operate relay 219. Relay 219, in operating, closes a circuit to operate relay 103 in the selector circuit, Fig. 1, which circuit can be traced from battery, winding of relay 103, conductors 105 and 252, contacts 253 of relay 243, contacts 254 of relay 219 and

to ground at contacts 246 of relay 217. Relay 225, in operating, also connects ground at its contacts 229 to maintain a busy condition on conductor 247 leading to the connector multiple CM. The withdrawal of the plug also causes relay CS in the cord to release thus lighting lamp C.

When the calling operator reinserts the plug for the first time, relay 202 operates to ground at contacts 206 of relay 207 as heretofore described. Relay 202 in closing its contacts causes the operation of relay 209 in an obvious circuit and also the operation of relay 210, the circuit for which can be traced from battery, winding of relay 210, contacts 212 of relay 213 and to ground at contacts 214 of relay 202. Relay 209, in operating, closes a circuit to operate relay 243 which can be traced from battery, winding of relay 243, contacts 289 of relay 240, contacts 290 of relay 209, contacts 291 of relay 207 and to ground at contacts 292 of relay 219. Relay 243, in operating, locks to ground in the following circuit: battery, winding of relay 243, contacts 270, contacts 254 of relay 219 and contacts 246 of relay 217 to ground. Relay 243, in operating, also opens at contacts 242 the energizing circuit for relay 221 and relay 100 in the selector circuit, both of which relays release. Relay 221 is slow in releasing, but when released, causes the operation of relays 240, 205 and 271, the circuits for which can be traced from ground on contacts 272 of relay 221, contacts 273 of relay 219, contacts 274 of relay 231 and thence over parallel circuits to battery; one of which extends through the windings of relays 271 and 240 and the other, through contacts 275 of relay 217 and the winding of relay 205. Relays 271, 240 and 205 operate. Relay 225 being slow to release does not retract its armature immediately upon the release of relay 221 and, therefore, it is held up to ground at relay 217 as soon as relay 205 operates. This holding circuit can be traced from battery, winding of relay 225, contacts 277 of relay 205, contacts 245 of relay 230 and to ground at contacts 246 of relay 217. When relay 240 operates it closes a circuit to hold relay 209 energized which circuit may be traced from battery, winding of relay 209, contacts 293 of relay 240, contacts 290 of relay 209, contacts 291 of relay 207, contacts 292 of relay 219 to ground. Relay 240, in operating, also reconnects the operator to the repeating coil and recloses the circuit for the supervisory relay CS, thus operating the relay 284 and again putting out the supervisory lamp C.

When the plug is withdrawn from the jack the second time, relays 202 and 210 release, all other relays being locked up. When relay 210 releases it removes a shunt, around the windings of relays 281 and 227;

and contacts 235 of relay 210 remain closed while relay 210 operates, thus inserting these relays (281 and 227) in series with relay 230. Due to the fact that relay 281 has a high resistance winding, the resistance of the trunk loop is thereby increased to such a figure that relays 230 at the calling end and 330 and 331 at its distant end of the trunk cannot hold operated and they, therefore, release. Relay 281, however, operates in this circuit and at its contacts 294 supplies ground to hold relay 225 operated, which would otherwise release when relay 230 released. This circuit can be traced from battery, winding of relay 225, contacts 277 of relay 205, and contacts 294 of relay 281 to ground.

By reason of the fact that the energizing circuit for the supervisory relay 384 at the distant exchange is completed through the make contacts 385 of relay 331, it will be evident that the alternate release and operation of relay 331 due to the alternate increase and decrease of the trunk resistance caused by the calling operator's alternate plugging out and in, will cause the distant called operator's cord supervisory AS' to follow the removal and insertion of the plug at the calling end, thus causing lamp A' to flash to indicate to the operator that she is wanted.

Disconnection.

When the conversation is completed and the plug at the calling end is removed, the distant operator's supervisory lamp A' will be steadily lighted as will be evident from the above description. When the called operator removes plug AP' from jack 301, relays 302 and 384 are released, followed by relays 309 and 310. When relay 310 releases, relay 331 and its associated battery is disconnected from the trunk and when relay 310 completes its back contacts 337, relays 331 and 327 are connected in series with each other and battery, thus operating relay 327 and holding relay 331 operated. When relay 327 operates it connects battery through resistance 362 to the trunk in place of through relay 331 and also relay 327, in operating, breaks at its contacts 326 the holding circuit for relay 325 which now releases and restores all the remaining operated relays to normal including relay 316. The release of relay 316 removes ground from the sleeve of jack 301 thus extinguishing lamp A' in the cord. Relay 317, in releasing, opens the circuit for relays 327 and 331 and removes ground from the trunk. Relay 327, in releasing, removes at its front contacts 363 battery from the trunk, thus releasing relay 281 at the calling end of the trunk. Relay 281, in releasing, opens the holding circuit of relay 225 which releases and causes the return to normal of all re-

ays at the calling end. Both ends of the trunk are now in normal condition. When plug 200 at the calling exchange was removed supervisory relay CS released and closed its back contacts. Whether lamp C lighted or not at this time depended on whether the answering plug AP was inserted in a line jack having battery on its sleeve contact.

10 What is claimed is:

1. In a telephone exchange system, a trunk line, an operator's position at each end of said trunk line, a cord circuit at each of said operators' positions connected to the trunk line, a signal for each of said cord circuits, a bridge at each end of said trunk line for controlling its associated signal, means including electrical current for controlling said bridge, and means controlled by the operator originating the connection for causing the application of the current to be shifted from one end of the trunk to the other.

2. In a telephone exchange system, a trunk line, an operator's position at each end of said trunk line, a cord circuit at each of said operators' positions connected to the trunk line, a signal for each of said cord circuits, a bridge at each end of said trunk line for controlling its associated signal, means including electrical current for controlling said bridge, and means operated in response to flashing by the operator originating the connection for shifting the application of current from one end of the trunk to the other and for maintaining the trunk busy during the flashing period.

3. In a telephone system, a trunk line extending between operators' positions of two exchanges, a supervisory circuit, sources of current therefor, one of said current sources being connected in said circuit at the originating operator's position upon the establishment of a connection between operators over said trunk line, and means responsive to the disconnection from and reconnection to the trunk by the operator originating the connection for disconnecting said one source of current from the originating position and connecting the other of said sources to the distant operator's position.

4. In a telephone system, a trunk extending between two exchanges, operators' link circuits thereat adapted to be connected to each end of said trunk, a supervisory signal associated with each link circuit, a circuit for said signals including a source of current completed when both of said link circuits are connected to the trunk, said source of current being connected in said circuit at the exchange originating the trunk connection, and means responsive to the disconnection from the trunk and the reconnection thereto of the link circuit at the originating exchange for removing said current source from the supervisory circuit at the originat-

ing exchange and for inserting another source in said supervisory circuit at the distant exchange.

5. In a telephone exchange system, a trunk extending between two distant operators' positions, a supervisory signal circuit therefor including signal devices at each of said operators' positions, sources of current therefor, one of said current sources being connected in said supervisory circuit at the operator's position originating the establishment of a connection, and means responsive to the disconnection from and reconnection to the trunk by the operator originating the connection, while the distant operator is connected to the trunk, for disconnecting said one source of current from the originating operator's position and connecting another of said sources of current in said circuit at the distant operator's position.

6. In a telephone exchange system, a two way inter-exchange trunk, an operator's cord circuit adapted to be connected to each end thereof to establish an inter-exchange connection, a supervisory signal circuit including direct current extending between cord circuits over said trunk when said inter-exchange connection is established, said current being connected in the supervisory circuit at the exchange originating the inter-exchange connection, and means responsive to the removal and insertion of the originating exchange cord circuit plug for transferring the connection of current from the originating to the called exchange end of the supervisory circuit.

7. In a telephone system, a calling and a called exchange, a two-way trunk line therebetween, a battery connected therein at the calling exchange upon connection to said trunk by said calling exchange, and automatic means responsive to disconnection from the trunk by the calling exchange after the called exchange has connected with the trunk for holding said trunk busy at the calling end for disconnecting said battery at the calling end and for connecting a similar battery in the trunk at the called exchange.

8. In a telephone system, a trunk line extending between a calling operator's position at one exchange and a called operator's position at another exchange, operator's cord circuits thereat adapted to connect to each end of said trunk, supervisory signals associated with said cord circuits, a source of current for controlling said signals, and means, actuated by the disconnection of the cord circuit from the trunk at the calling exchange while the cord circuit at the called exchange is connected to the other end of the trunk, for holding the trunk busy at the calling end during the period that said operator's cord circuit at said calling exchange

is disconnected and said operator's cord circuit at said called exchange is connected to the trunk, and for connecting current with said trunk at the called end.

5. 9. In a telephone system, a trunk line extending between a calling operator's position at one exchange and a called operator's position at another exchange, operator's cord circuits thereat adapted to connect to each 10 end of said trunk, supervisory signals associated with said cord circuits, a source of current controlling said signals associated with said trunk at the called end thereof upon disconnection therefrom of the calling 15 operator's cord circuit while the called operator's cord circuit is connected to the trunk, and a relay in series with said source of current for causing said trunk to test busy at the calling end during the period that said 20 calling operator's cord circuit is disconnected from the trunk and said called operator's cord circuit is connected thereto.

10. In a telephone system, trunk lines extending between operators' positions in two

exchanges, a supervisory circuit and sources 25 of current therefor, one of said current sources being connected to said circuit at the originating operator's position upon the establishment of a connection between the operator's position and said trunk line, 30 means responsive to disconnection from the trunk by the operator originating the connection for holding said trunk busy at the originating exchange during the period that said connection is broken thereat and the 35 connection with said trunk is maintained at the distant operator's position, and means also responsive to the breaking of the originating operator's connection for disconnecting said one source of current from the 40 originating end of said circuit and for connecting another of said sources of current in said circuit at the distant operator's position.

In witness whereof I hereunto subscribe 45 my name this 14th day of September A. D., 1923.

WARREN W. CARPENTER.
